WITNESS

UNITED STATES PATENT OFFICE.

LEO K. STAFFORD, OF DETROIT, MICHIGAN, ASSIGNOR TO THE STAFFORD ROLLER-BEARING CAR TRUCK CORPORATION, OF LAWTON, MICHIGAN, A CORPORATION OF NEW JERSEY.

JOURNAL BOX.

Application filed January 27, 1920. Serial No. 354,425.

To all whom it may concern:

Be it known that I, LEO K. STAFFORD, a citizen of the United States, residing at Detroit, in the county of Wayne and State 5 of Michigan, have invented new and useful Improvements in Journal Boxes, of which the following is a specification.

This invention relates to roller bearings for railway trucks and the present invention 10 is an improvement over that forming the subject matter of an application filed by me on Sept. 6, 1919, Serial No. 322,027.

One of the objects of the present invention is to provide two or more series of rollers 15 between the box and spindle, the rollers of one series having independent movement in relation to the other rollers so as to reduce the wear of the rollers and prevent breakage of the parts and make the bearing more 20 flexible than it would be if a single series of rollers was used.

Another object of the invention is to connect the roller bearing retaining member to the spindle so that it will rotate with the 25 spindle and with the roller cage so as to reduce the wear and friction between said member and the cage.

Still another object of the invention is to provide means whereby the parts may have 30 a certain amount of movement in a vertical plane so as to compensate for the tilting movement of the axle due to uneven parts of the track.

This invention also consists in certain 35 other features of construction and in the combination and arrangement of the several parts, to be hereinafter fully described, illustrated in the accompanying drawings and specifically pointed out in the appended 40 claims.

In describing my invention in detail, reference will be had to the accompanying drawings wherein like characters denote like or corresponding parts throughout the several views, and in which:—

Figure 1 is a cross sectional view through a boxing and spindle showing the manner of carrying out my invention.

Figure 2 is an end view of the parts 50 shown in Figure 1.

Figure 3 is a longitudinal sectional view with parts broken away.

Figure 4 is a side view with parts in section.

Figure 5 is a perspective view of one of the rollers.

Figure 6 is a sectional view showing a modification.

Referring to Figures 1 to 5, inclusive, the boxing is indicated at 1 and this boxing is located between the upper and lower projections 2 of the truck, which are connected together by the bolts 3 which carry the spacing sleeves 4, the boxing being arranged between said bolts. The top of the boxing is provided with the concave recess 5 which receives the semi-circular member 6 carried by the upper member of the truck. As will be seen the bottom piece of the truck is spaced from the bottom of the boxing so that said boxing may have vertical play to permit a rocking movement. This rocking movement being limited by the lugs 7 formed on the sides of the boxing and engaging with the bolts or their sleeves.

A case hardened sleeve or tube 8 is inserted in the bore of the boxing and this tube is provided with a longitudinally extending rib 9 which engages the longitudinal groove 10 formed in the boxing. A case hardened tube 11 is placed on the spindle 12 of the axle and this tube is also provided with a rib 13 engaging a groove 14 in the spindle to prevent turning of the tube on said spindle. As shown in Figure 3 the tube extends through the wheel and is provided with an offset portion 15 which forms a shoulder which engages the shoulder 16 on the spindle.

The rollers 17 are carried by the rings 18 and these rings are connected together by the rods 19. As shown I use two series of rollers, each series being carried by a pair of rings with the middle rings in contact with each other. Each roller has its ends rounded as at 20 so as to allow for the tilting movement of the axle in the boxing when the car is passing over uneven portions of the track. The rings may be provided with the nipples shown in the before mentioned application and engaging the conical openings 21 in the ends of the rollers.

The roller cage is retained in position between the case hardened tubes by means of the retaining member 22 which is made in the form of a cap for fitting over the end of the spindle. This member has screw threaded engagement with the end of the

tube 11 and is bolted to the end of the spindle by the bolts 23. In this way the retaining member rotates with the spindle and the cage so as to reduce wear of the said member and the outer ring of the cage. This arrangement also permits the cage to be snugly held in position between the shoulder on the tube 11 and the retaining member.

Holes 24 are formed in the lower part 19 of the tube 8 and the lower wall of the bore of the boxing, these holes communicating with the oil well 25 of the boxing. The end of the bore of the boxing is closed by the screw cap 26 and this cap has formed 15 therein a filling opening 27 which is closed by a screw plug 28.

In the modification shown in Figure 6 the boxing 1' is made integral with the ends of the truck, shown at 2' and in order to 23 permit the vertical play of the parts when the car is passing over uneven portions of the track I make the bore 2' of the boxing of substantially elliptical shape so that the rollers 17' carried by the annular cage 18' 23 will be spaced from the lower portion of the boxing and thus permit the vertical play above mentioned. In other respects this form of the invention is similar to that above described.

It will thus be seen that when the car is passing over uneven portions of the track or over loose joints of the rails where the axle will be tilted this movement will be compensated for by the vertical play between the parts so that the rollers will not be wedged between the tubes and thus subjected to great wear. Also by having the two or more rollers in place of the one long roller there is no danger of the rollers breaking under the uneven strain as one roller can rotate independently of the other. By having the ends of the rollers rounded the tilting action will not chip off the ends of the rollers as would be the case if the rollers 45 were made with square ends. By securing

the retaining member for the roller cage to the spindle this member will rotate with the cage and spindle so that the wear between the outer ring of the cage and said member will be reduced to the minimum and the cage may be held against longitudinal movement by said member.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A roller bearing for railway trucks comprising a boxing having a bore therein for receiving the axle spindle having lubricant openings in the bottom thereof, the wall of the bore and the spindle each being provided with a groove, a case hardened tube located in the bore having openings registering with the openings in the boxing and having a rib thereon engaging the groove, a case hardened tube carried by the spindle and having an interior rib engaging the groove in the spindle, a roller cage located between said tubes, said cage consisting of a series of rings and bars connecting the rings together, the inner rings contacting with each other, a plurality of rollers carried by each pair of rings and retaining means for the cage.

2. A roller bearing for railway trucks comprising a box having a bore of elliptical shape for receiving the axle spindle, a case hardened tube located in the bore, said tube also being of elliptical shape, a case hardened tube carried by the spindle, a roller cage of circular shape located between said tubes and roller bearings carried by said cage.

In testimony whereof I affix my signature,

LEO K. STAFFORD.
